UNITED STATES PATENT OFFICE.

WALTER H. TIBBALS, OF SYRACUSE, NEW YORK.

FIRE-EXTINGUISHER.

1,214,971.

Specification of Letters Patent.

Patented Feb. 6, 1917.

Application filed May 27, 1913. Serial No. 770,119.

To all whom it may concern:

Be it known that I, WALTER H. TIBBALS, of Syracuse, in the county of Onondaga, in the State of New York, have invented new and useful Improvements in Fire-Extinguishers, of which the following, taken in connection with the accompanying drawings, is a full, clear, and exact description.

This invention relates to certain improvements in hand fire extinguishers having a liquid chamber in one end and an air chamber in the other end for receiving, respectively, a fire-extinguishing liquid and air under abnormal pressure for producing a permanently charged extinguisher without the use of chemicals or chemically generated gases.

The main object is to render the device air-tight so that it may contain the liquid under pressure for indefinite periods of time.

Another object is to simplify the device to such an extent as to eliminate all unnecessary joints or attachments and supporting the siphon pipe solely by the valve case independently of the cylinder.

A further object is to extend the pipe from the valve case through both chambers so as to connect the valve chamber at one end with the opposite end of the liquid chamber to the exclusion of any communication between the pipe and air chamber.

Another object is to screw the plug for the inlet in the bottom of the tank in such manner as to be wholly within the plane of the marginal edge thereof to allow the tank to stand flat upon its bottom in order that it may be supported in a vertical position.

Other objects and uses will be brought out in the following description.

40 In the drawings—

Figure 1 is a vertical sectional view of a hand fire extinguisher embodying the various features of my invention.

Fig. 2 is an enlarged sectional view 45 through the central portion of the bottom of the tank showing the plug for the inlet and the manner of screwing it in operative position.

Fig. 3 is an inverted plan of one of the 50 plug sections showing the V-shape groove therein for receiving the packing.

As illustrated, this fire extinguisher comprises a tubular sheet metal cylinder —1— having opposite end heads —2— and —3—, 55 preferably of the same metal, forming the bottom and top respectively of the container

and having their marginal edges fitted and secured to the corresponding ends of the cylinder —1— to form hermetically sealed joints to prevent any possibility of leakage of air, gas or liquid, the bottom head —2— being arched upwardly or inwardly so that its central portion lies in a plane some distance above that of its marginal edge to allow the device to stand in an upright position upon a flat support.

A reinforcing bushing —4— is permanently secured in a central opening in the bottom head —2— to form an air- and water-tight joint therewith and is provided with a centrally threaded opening —5— for receiving a screw plug —6—, said plug being provided with an annular recess —7— and upturned marginal flange —8— surrounding the recess for receiving and inclosing a packing —9— preferably of lead or equivalent material to prevent any possibility of leakage of air, gas or liquid when the plug is screwed up tightly, the upturned marginal flange —8— serving to prevent outward spreading of the packing.

As additional means for preventing leakage at this point, the underside of the bushing —4— is provided with a V-shape groove —10— into which a portion of the lead packing —9— is forced when the plug is screwed up tightly, the flange —8— being of substantially the same diameter as the external diameter of the adjacent portion of the bushing so as to form a turning connection therewith to more positively hold the lead packing against being forced laterally and upwardly, thereby confining and utilizing the entire packing as an effective medium to prevent leakage.

The object of this opening centrally in the bottom of the tank is to permit a proper amount of the fire extinguishing liquid as —a— to be injected into said tank after which the plug —6— is inserted and screwed up tightly in a manner described to prevent leakage, it being understood that when the tank is placed in its normal upright position, the joints between the plug and bottom of the tank are always under liquid seal, thereby additionally reducing the liability of leakage.

A valve case —11— is provided with a pendant portion inserted into a central opening —12— in the top head —3— of the tank and permanently secured to said head in such manner as to form a perma-

uent tight joint which is hermetically sealed against leakage of air, gas or liquid and is never removed when once secured in operative position and becomes practically an 5 integral part of the head, but, in order to additionally secure the joint against leakage, the inner end of the joint is soldered or brazed by additional metal —13—.

This valve case is provided with a valve 10 chamber —14— surrounding the inner end of a needle valve —15— and communicating with a vertical passage —16— in which is tightly secured one end of a siphon tube —17—, the latter extending downwardly to 15 a point in proximity to the bottom of the tank and together with a discharge passage —18— in the valve case forms a single passage for the inlet of air or gas under pressure and for the discharge of the fire-extinguishing fluid the exit passage —18— being located at one side of the axis of the pipe —17—.

The valve casing —11— is T-shaped, the head thereof being provided with a threaded aperture —19— at one side of the axis of the pipe —17— opposite the exit —18— and coaxial therewith for receiving the threaded portion of the needle valve —15—, the outer end of the valve stem being provided with a hand piece —20— by which the valve may be opened and closed to and from its seat as —21—, the joint between the valve stem and valve case being protected against leakage by a suitable stuffing box 30 or gland —22—.

The valve —15— is aligned with the discharge passage —18— and valve seat —21—, which latter is formed on the inner end of the passage —18— and together with said 40 passage is located at one and the same end of the valve chamber —14— at one side of the vertical passage —16— so that the pressure of the liquid toward the outlet is in the same direction as the closing of the valve tending 45 to hold said valve in its closed position and at the same time by extending the chamber —14— entirely around the valve, it is evident that the pressure is the same at all sides thereof tending also to center and hold 50 the valve to its seat.

The outlet passage —18— leading from the valve chamber —14— is relatively small but terminates in an annular enlargement —23— which is threaded internally and 55 adapted to receive a connection with a pump or other air compressing device.

It will be seen upon reference to the drawing that the pipe —17— is supported wholly by the valve case —11— independently of 60 the cylinder and extends entirely from said valve case at one end to a point in proximity to the opposite end of the cylinder through both the air chamber and the liquid chamber and communicates only with the liquid 65 chamber and with the valve chamber —14—

so as to cause the liquid under air pressure to fill the tube or pipe, and also the valve chamber and thereby maintain a liquid seal at the valve seat.

In charging the hand extinguisher, the 70 plug —6— is removed and the tank inverted after which a sufficient quantity of the fire-extinguishing liquid is inserted through the opening —5—.

In charging or re-charging the hand extinguisher, the valve —15— is first closed tightly and the plug —6— is then removed while the tank is in an inverted position after which the fire-extinguishing liquid may be poured or injected into the cylinder 80 through the opening —5— in a quantity sufficient to fill the tank about two-thirds full more or less whereupon the plug —6— may be reinserted and tightly screwed in place to avoid any possibility of leakage 85 and the tank restored to its upright position.

The valve —15— is then opened and an air pump or equivalent air-compressing device is attached to the nozzle —23— and 90 operated to force the air through the channel —18—, passage —16— and pipe —17— into the interior of the tank, which air under pressure rises through the liquid to the surface thereof within the remaining air 95 space as —24— in the top of the cylinder until such pressure approximates seventy-five (75) to ninety (90) pounds more or less, thereby displacing the liquid sufficiently to force a portion thereof up through the tube 100 —17— and into the valve chamber —14— where it surrounds the valve and forms a liquid seal for the valve seat and at the same time, the liquid in the bottom of the tank covers the joint between the plug 105 —16— and bottom of the tank to form a liquid seal therefor, thereby establishing a liquid seal for all movable joints and increasing the ability of the tank to hold the pressure for an indefinite period of time, 110 it being understood that before the air pressure is removed after reaching the desired degree in the tank, the valve —15— is closed firmly against its seat to prevent the escape of the liquid or air. 115

The whole device with the fire-extinguishing liquid therein under abnormal pressure constitutes an article of manufacture which is always ready for use in case of fire and may be easily carried from place to place or installed in automobiles, motor boats and other places in a comparatively small compact space.

What I claim is:

A hand fire extinguisher comprising an 125 air-tight cylinder having a liquid chamber in one end and an air chamber of less length than the liquid chamber in its opposite end, a valve case secured to one end of the cylinder and provided with a pipe extending 130

through both chambers to a point in proximity to the opposite end of the cylinder and communicating only with the liquid chamber and valve case, said pipe being supported solely by the valve case independently of the cylinder, the valve case having an exit passage wholly to one side of the axis of the pipe, and a needle valve screwing into the valve case at the opposite side of said

axis and extended across such axis for controlling the exit passage.

In witness whereof I have hereunto set my hand this 20th day of May, 1913.

WALTER H. TIBBALS.
